Atty.

UNITED STATES PATENT OFFICE

KENNETH M. RONAN, OF WAYNE, MICHIGAN, ASSIGNOR TO MANNING & CO., OF CHICAGO,
ILLINOIS, A CORPORATION OF ILLINOIS

CHAIR

Application filed September 13, 1930. Serial No. 481,639.

This invention relates to improvements in chairs and it consists of the matters herein-after described and more particularly pointed out in the appended claims.

The primary object of the invention is to provide a chair especially adapted for airplane use, which chair though light in weight is indeed strong and at the same time is comfortable and easy for the occupant and may be made at a substantially low cost of production.

Another object of the invention is to provide a chair of this kind having a frame work made up of lengths of light weight tubing so formed and welded together as to cooperate to the best advantage in forming a chair having all characteristics desired for one employed in airplane work.

These objects of the invention as well as others, together with the many advantages thereof will more fully appear as I proceed with my specification.

In the drawing:

Fig. 1 is a perspective view of a chair embodying my invention.

Fig. 2 is a perspective view of the chair with the seat cushion and upholstery removed to better illustrate the structure of the welded tubular frame and associated seat bottom.

Fig. 3 is a detail transverse vertical sectional view on an enlarged scale through one side of the seat frame and associated parts as taken on the line 3-3 of Fig. 2.

Fig. 4 is a detail vertical sectional view also on an enlarged scale through the front portion of the seat frame and associated parts as taken on the line 4-4 of Fig. 2.

Referring now in detail to that embodiment of the invention illustrated in the accompanying drawing:—1 indicates as a whole the frame of the chair which is preferably made up entirely of thin light metallic tubing of substantially small diameter. Said frame includes substantially upright front legs 2-2 and substantially upright rear legs 3-3, the front legs each having a rearwardly extending substantially horizontal portion 4 that is welded to the rear legs to provide the side rails of the frame. The front legs as well as the rear legs are provided at their

bottom ends with horizontally bent extensions or feet 5 whereby stability is provided for the frame as well as a means of attaching the chair in place to the floor of the cabin or cockpit of an airplane.

Associated with the front legs is an inverted V-shaped brace the bottom ends of the diverging arms 6 of which are welded to the front legs near the feet thereof, the crotch or apex 7 of said brace being positioned substantially flush with the top ends of said front legs. Associated with the rear legs is an inverted V-shaped brace, the bottom ends of the diverging legs 8 of which are welded to said rear legs near the feet thereof, the crotch 9 of the brace being disposed in substantially the plane of the attachment of the rails 4-4 with said rear legs.

The front legs are pitched slightly rearwardly at their top ends toward the rear while the rear legs which are pitched slightly forwardly, include upright extensions 11, that form those portions of the frame providing a back rest for the chair. The top end of each extension is connected to the bottom portion of the other extension by a diagonal brace bar 12, the two bars crossing each other to give an X-shape thereto and being welded together at their point of intersection and being welded at their ends to said upright extensions as best shown in Fig. 2.

13 indicates as a whole an inverted U-shaped member including side bars 14-14 and a top cross bar 15. The top ends of the rear leg extensions 11 meet with and are welded to the said cross bar 15 while the legs of said U-shaped members extend downwardly and forwardly, to engage and be welded to the outside of the horizontal rail portion and to the bottom end of an associated front leg 2. A brace 14^a connects the bottom end of each rear leg, with the associated leg 14 of said U-shaped member at a point approximately in the plane of the portions 4 before mentioned. The side bars 14-14 of said U-shaped member not only brace the back rest members but also provides the side arms for the finished chair.

Associated with the frame thus far described is a seat bottom 16 including an open

85

90

95

100

frame comprising side rails 17 and front and rear rails 18 and 19 respectively all preferably of wood, the frame being normally closed by a panel like seat bottom 20. When 5 the seat bottom is in place upon the frame before described, the front and rear rails thereof engage upon and are secured to the crotches 7 and 9 respectively of the inverted V-shaped braces before mentioned by bolts 10 21 and 22 respectively, while the side rails of the seat frame rest upon the horizontal rail portions 4 of the front legs and are secured thereto by bolts 23, 24 and 25 respectively. In this respect it is pointed out that 15 each side rail of the seat frame is provided with a notch or recess 26 to accommodate the side bars 14 of the U-shaped members before mentioned.

The frame thus far described is enclosed 20 in a suitable covering of fabric 27 or the like and a deep seat cushion 28 is provided upon the seat frame. Of course, suitable upholstery may be provided for the back rest and each leg with its intimately associated 25 braces may be enclosed by said covering as best shown in Fig. 1. In this respect it is pointed out that the entire frame work is concealed by said covering but triangular spaces 29 are provided at the sides and at the 30 front and rear of the chair as a whole. Thus the smaller luggage may be stowed under the seat.

When the chair is in place in the cabin of an airplane, its feet may be securely attached to the floor thereof in any suitable manner.

The construction described provides a strong light weight chair especially adapted for airplane use, and one that cannot be easily racked or twisted out of shape or become loose at any of the connections between the associated parts. Again, the chair is comfortable for the occupant.

While in describing the invention, I have 45 referred in detail to the form, arrangement and construction of the parts thereof, the same is to be considered merely as illustrative so that I do not wish to be limited thereby to except as may be specifically set forth in 50 the appended claims.

I claim as my invention:—

1. A chair embodying therein a frame made of metallic tubing and comprising pairs of front and rear legs, the rear legs 55 having upright extensions forming a part of the back for the frame and the front legs having rearward extensions welded to the rear legs and forming the side rails for the frame, an X-shaped brace connecting the 60 upright extensions together and welded at its ends thereto and a member connecting the top ends of said upright extensions together and welded thereto and including downwardly and forwardly extending portions crossing and welded to said side rails

and terminating at and being welded to the bottom ends of said front legs.

2. A chair embodying therein a frame made of metallic tubing and comprising pairs of front and rear legs, the rear legs having 70 upright extensions forming a part of the back for the frame and the front legs having rearward extensions welded to the rear legs and forming the side rails for the frame, an X-shaped brace connecting the upright extensions together and welded at its ends thereto, a member connecting the top ends of 75 said upright extensions together and welded thereto and including downwardly and forwardly extending portions welded to associated side rails and front legs respectively and a brace connecting each rear leg to the associated downwardly and forwardly extension portion of said member and welded at its ends thereto.

3. A chair embodying therein a frame made of metallic tubing and comprising pairs of front and rear legs, the rear legs having upright extensions forming a part of the back for the frame and the front legs 90 having rearward extensions welded to the rear legs and forming the side rails for the frame, V-shaped braces welded to and connecting the legs of each pair of legs together, an inverted U-shaped member having its 95 cross bar welded to and connecting the top ends of said upright extensions together and having side bars extending downwardly and forwardly and welded to said side rails and front legs respectively and a seat bottom 100 frame engaged on and secured to said V-shaped braces and said side rails respectively.

4. A chair embodying therein a frame made of metallic tubing and comprising pairs of front and rear legs, the rear legs having upright extensions forming a part of the back for the frame and the front legs having rearward extensions welded to the rear legs and forming the side rails for the frame, V-shaped braces connecting the legs of each 110 pair of legs together, an inverted U-shaped member having its cross bar welded to and connecting the top ends of said upright extensions together and having side bars extending downwardly and forwardly and 115 welded to said side rails and front legs respectively, braces welded to and connecting the rear legs and said side bars of said U-shaped member together and a seat bottom 120 frame engaged upon and secured to said V-shaped braces and said side rails respectively.

5. A chair embodying therein a frame comprising pairs of front and rear legs, the rear legs having upright extensions forming 125 part of the back for the frame and the front legs having rearward extensions connected to said rear legs and forming the side rails for the frame, an X-shaped brace connecting said extension together, V-shaped braces con- 130

necting the legs of each pair of legs together, each V-shaped brace having its crotch disposed in the approximate plane of said side rails, an inverted U-shaped member having a cross bar connecting the top ends of said extensions together and having side bars extending downwardly and forwardly to cross and be secured to the side rails and also secured to the bottom ends of the associated front legs and a brace connecting each side bar and associated rear leg together.

In testimony whereof, I have hereunto set my hand, this 4th day of September, 1930.

KENNETH M. RONAN.
